(57) **CLAIM**

The ornamental design for a wrist brace, as shown and described.

DESCRIPTION

FIG. 1 is a perspective view of a wrist brace showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of area 9 shown in FIG. 5;

FIG. 10 is an enlarged view of area 10 shown in FIG. 7; and, FIG. 11 is a perspective view of the wrist brace of FIG. 2 as it would be positioned during use.

The broken lines showing a human hand in FIG. 11 represent environmental subject matter only and form no part of the claimed design. The broken lines shown around the perimeter of the wrist brace represent stitching and form part of the claimed design.

The dashed lines in the drawings depict stitching lines that form part of the claimed design.
